(57) **CLAIM**

The ornamental design for a motorcycle lower leg and axle cover with a diamond motif, as shown and described.

DESCRIPTION

FIG. 1 is a bottom three quarter angle view of a motorcycle lower leg and axle cover with a diamond motif showing my new design;

FIG. 2 is a left elevational view thereof;

FIG. 3 is a right elevational view thereof;

FIG. 4 is a front elevational view thereof;

FIG. 5 is a rear elevational view thereof;

FIG. 6 is a top view thereof; and,

FIG. 7 is a bottom view thereof.

The broken lines show portions of the motorcycle lower leg and axle cover with a diamond motif that form no part of the claimed design.
